UNITED STATES PATENT OFFICE.

SAMUEL J. DONNELLY, OF ONEONTA, NEW YORK.

BURIAL-CASKET.

1,099,285.

Specification of Letters Patent. Patented June 9, 1914.

Application filed March 21, 1914. Serial No. 826,381.

To all whom it may concern:

Be it known that I, SAMUEL J. DONNELLY, a citizen of the United States, residing at Oneonta, in the county of Otsego and State of New York, have invented certain new and useful Improvements in Burial-Caskets, of which the following is a specification, reference being had to the accompanying drawings.

10 This invention relates to improvements in burial caskets, and more particularly to caskets which are composed of plastic material in which a reinforcing structure is embedded.

15 An object of this invention is the provision of a burial casket, the casket comprising a body which is preferably composed of glass in which a reinforcing structure is embedded, and a cover for the body which is also formed of glass and in which a reinforcing structure is mounted, means being provided to form air tight joints between the body and the cover.

20 A further object of this invention is the provision of a burial casket comprising a body and a cover composed of plastic material, the body having metallic plates connected thereto to which the handles of the casket are connected.

25 With these and other objects in view, my invention consists in the novel construction, combination, and arrangement of parts to be hereinafter more fully described, claimed, and illustrated in the accompanying drawing, in which,

30 Figure 1 is a transverse sectional view of the casket; Fig. 2 is a longitudinal sectional view thereof; and Fig. 3 is a fragmentary perspective view showing the manner of connecting one of the handles to the casket.

35 Referring more particularly to the drawing, the casket comprises a body 1 and a cover 2, which are preferably composed of glass, the body having a marginal bead 3 formed thereon at its lower edge and transversely extending beads 4 formed on the bottom thereof. A peripheral bead 5 is also formed on the side and end walls of the body intermediate of their upper and lower edges, and a reinforcing structure which is composed of aluminum or other suitable metal is embedded in the body. The reinforcing body comprises a lower rectangular frame 6, which is embedded in the bead 3, the side portions of the frame being connected by transverse rods 7 which are em-

bedded in the transversely extending beads 4 on the bottom of the body. An upper rectangular frame 8 is embedded in the bead 5, the upper and lower frames being connected by the vertical metallic strips 9 which are curved at their upper and lower ends for engagement around the rods of the upper and lower frames 6 and 8.

35 The side and end walls of the body are formed with a lateral flange 10 adjacent their upper edges and the cover 2 has a groove 11 formed therein adjacent its edges, the groove being adapted to engage the upper extremities of the side and end walls of the body and the edges of the cover engaging the flange 10 on the body. The flange 10 is provided with a plurality of spaced openings 12, and the projecting edges of the cover are also provided with a plurality of spaced openings 13, the openings 12 and 13 registering to receive the fastening bolts 14, upon which the nuts 15 are mounted to securely hold the cover to the body. The cover 2 is also provided with a reinforcing 80 rectangular frame 16.

35 Spaced pairs of handle supporting plates 17 are connected at intervals to the body by rivets 18, the plates being curved for a portion of their length as at 19, to engage 85 the bead 5 of the body, and connecting each pair of plates is a rod 20 upon which a handle 21 is pivotally mounted, by means of which the casket may be carried.

40 From the above description, taken in connection with the accompanying drawings, it will be seen that I have provided a burial casket which is composed of glass and the body and cover of which are provided with novel reinforcing structures, the handles of 90 the casket being connected to metallic supporting plates, so that slipping or breaking of the body of the casket by the handles is prevented.

45 Having thus fully described my invention, what I desire to secure and claim by Letters Patent is:—

1. A casket comprising a body and a cover, said body having a bead formed on the lower corners thereof, the bead projecting below the bottom of said casket, a rectangular reinforcing wire frame embedded in said bead, transversely extending beads formed on the bottom of said casket, transverse wires mounted in said transverse beads 110 and connected at their opposite ends to the side portions of said rectangular frame, a

bead formed on the walls of said body between its upper and lower edges, a rectangular reinforcing frame embedded in said last mentioned bead, vertical strips connected at their opposite ends to said rectangular frames, and means for fastening the cover to said body.

2. A plastic burial casket comprising a body and a cover, a bead formed on the walls of said body between their upper and lower edges, a reinforcing member embedded in said bead, handle supporting

plates connected to the side and end walls of said body, said plates having curved portions for engagement with said bead, and handles pivotally carried by said plates, as and for the purpose described. 15

In testimony whereof I hereunto affix my signature in the presence of two witnesses.

SAMUEL J. DONNELLY.
